UNITED STATES PATENT OFFICE.

ADOLPH BLUMENKROHN, OF NEW YORK, N. Y.

DESIGN FOR TRIMMING FOR BELTS.

SPECIFICATION forming part of Design No. 20,049, dated July 22, 1890.

Application filed June 26, 1890. Serial No. 356,880. Term of patent 7 years.

To all whom it may concern:

Be it known that I, ADOLPH BLUMENKROHN, a citizen of the United States, residing at New York city, in the county and State of New York, have invented and produced a new and original Design for Trimming and Belts, of which the following is a specification, reference being had to the accompanying drawing, forming a part thereof, and which represents a plan view of the design.

The design consists of a central slide-like figure A and an angular figure B at each side

of the slide-like figure, which angular figures are represented as composed of a series of closely-grouped circular figures b. The marginal contour of the entire design closely approximates that of a diamond figure.

I claim—

A design for trimming and belts, substantially as herein shown and described.

ADOLPH BLUMENKROHN.
